GLASS HOLDING CONSTRUCTION

Reginald C. Steeple, San Mateo, Calif.

Application July 12, 1933, Serial No. 680,062

10 Claims. (Cl. 20—56.4)

My invention relates to the framing and supporting of glass, and more particularly to a construction for holding the glass panes of display windows, such as found in store fronts or show cases.

It is among the objects of my invention to provide a construction which facilitates the installation of glass panes.

Another object of my invention is to provide a structure comprising parts which are readily adjustable to meet the precise requirements of a given installation.

Another object of my invention is to provide a structure which maintains a firm and secure hold on the glass, yet which places no excessive strains in the glass pane.

A further object of my invention is to provide a construction which is artistic and which is readily adaptable to be made in conformity with any desired type of architecture.

The invention possesses other objects and features of advantage, some of which, with the foregoing, will be set forth in the following description of my invention. It is to be understood that I do not limit myself to this disclosure of species of my invention, as I may adopt variant embodiments thereof within the scope of the claims.

Referring to the drawings:

Figure 1 is a perspective view showing a sash embodying the improvements of my invention.

Figure 2 is a horizontal section showing the construction of my invention as embodied in a partition unit; and

Figure 3 is a side elevation of the same.

Figure 4 is a horizontal section showing the construction of my invention as embodied in a corner unit; and

Figure 5 is a side elevation of the same.

Figure 6 is a detail plan view of the set-plate employed in my improved sash construction; and

Figure 7 is a similar view of the set-plate employed in the division and corner units.

Figure 8 is a view similar to that shown in Figure 3 and illustrates the use of a tool in the installation of my improved division unit construction; and

Figure 9 is a detail view of this tool.

Figure 10 is a perspective view of a sash showing a modified form of my construction; and

Figure 11 is a transverse vertical section of the same.

In terms of broad inclusion, the glass holding construction embodying my invention comprises a pair of glass engaging bars. A toothed element is provided on one of the bars, and a deformable

element is provided on the other bar. Means are also provided for imbedding the teeth of the first element into the second element for locking the bars together.

In greater detail, and referring particularly to Figure 1, the glass holding construction of my invention as embodied in a sash structure comprises a stationary bar 2 and a cooperating movable bar 3, between which is held the glass pane 4. The stationary bar 2 comprises the gutter section 5 of the sash and is preferably channel-shaped, having a top flange 6 and a base flange 7.

The upper flange 6 of the stationary sash bar is preferably of I-beam section to provide a flat forward face for bearing against the glass 4. The base flange 7 of this bar is provided with a forwardly extending tongue 8, and is also provided with a longitudinally extending dove-tailed recess 9. The latter recess provides a seat for set-plate 11 having upwardly extending teeth 12. The dove-tailed seat provided for the plate 11 securely holds the latter, yet permits free longitudinal movement for adjustment of the plate along the bar.

The movable bar 3 comprises the glazing bar 25 of the sash, and is provided along its upper edge with a depending lip 13, providing a flat face for bearing against the glass 4. A flange or web 14 provided on the movable bar 3 comprises the tie bar of the sash construction, and is positioned to project between the flanges of the stationary bar and to overlie the toothed plate 11. A lip 16 is also provided on the movable bar 3 along the lower edge thereof, and cooperates with the flange 14 to provide a recess 17 for engaging the tongue 35 8 of the stationary bar. This interengaging means adds to the rigidity of the assembled structure and also aids in holding the movable bar in a given position during the assembly of the unit.

The means for locking the bars together involves an interaction between the toothed set-plate 11 and the tie bar 14. The plate 11 is made of a harder material than the tie bar 14 so that the teeth 12 may be pressed into the bar. For example, if the tie bar were made of aluminum 45 (formed as an integral part of an aluminum sash bar) the toothed plate 11 could be of hardened stainless steel; the idea being, of course to provide sufficient difference in the materials to cause the teeth 12 of the set-plate to imbed themselves in the tie bar 14 when the latter elements are clamped together. Other metals for these elements of my improved structure will immediately suggest themselves to those skilled in the art; it being understood that the aluminum-steel com-

bination suggested above is merely for purposes of illustration.

- The pressure for imbedding the teeth 12 is provided by a screw 18 bearing against the upper side of the tie bar and pressing the latter downwardly against the set-plate. After a sheet of glass has been set and the glazing bar 3 pressed forward against the glass with the hand or fingers until the proper degree of snugness is attained, the screw 18 is tightened to clamp down on the tie bar. This causes the teeth to become imbedded in the tie bar and thereby lock the sash bars 2 and 3 together. A substantially perfect fit with the glass is attained, irrespective of the thickness of the latter, because the teeth of the set-plate imbed themselves in the tie bar at any selected position of adjustment and without disturbing the relation between the parts. It will be understood that a very moderate pressure and consequent slight indentation of the teeth of the set-plate into the tie bar will be sufficient, when thus firmly held in position by the set screw, to overcome all possibility of slippage and thus lock the engaging members positively in position, one to the other. The tie bar 14 may be a continuous flange extending along the sash bar 3; or it may be discontinuous, with sections projecting inwardly only at spaced intervals. The set-plates 11 are adjustable along the bar 2 and as many as is deemed suitable or desirable may be provided. The clamping screws 18 are also spaced along the bar, as many being provided as is needed for giving the proper clamping action. The screws are preferably positioned to lean away from the glass 4 to give room for a workman to handle his screwdriver. To accommodate this angle of the screws the tie bar is provided with a tapered surface, thereby giving a positive and direct bearing for the screws.
- It will be noted that the upper flange 6 of the stationary bar 2 slopes rearwardly to provide a drain passage for collected moisture. Suitable drain holes 19 are provided along this passage for conducting the collected moisture downwardly, and suitable weep holes 20 are provided in the base flange 7 for draining out the water. Suitable grooves 21 in the bottom of the glazing bar 3 cooperate with the weep holes to provide for ventilation. The bottom of the stationary bar 2 is preferably recessed, as shown in Figures 1, 10 and 11, for receiving a mastic cementing or sealing compound.
- Figures 2 to 5 illustrate the principles of my invention as embodied in division and corner units, where the function of the structure is to provide a joint between plates of glass. In these cases the outer or glazing bar 22 engages or bridges the glass panes 23, and the tie bar 24 projects inwardly between the glass panes. A pair of inner bars 26 are provided in this type of construction, one on each side of the tie bar 24 and each engaging one of the glass plates 23.
- The bars 26 each have a longitudinally extending groove in which is seated a set-plate 27, after much the same manner of the set-plate 11 described in the sash construction of Figure 1. The elements are clamped together by a suitable bolt 28 passing through elongated apertures provided in the bars 24 and 26 and in the set plates 27. As in the sash construction, the set-plates are made of a harder material than that used in the tie bar, so that when the clamping bolt 28 is tightened the teeth of the set-plate will become imbedded in the tie bar.
- The inner end of the tie bar 24 is preferably

provided with flanges 29, against which a tool, such as that shown in Figures 8 and 9, may engage. The purpose of this tool, as shown in Figure 8, is to provide a simple and convenient means for bringing the bars snugly against the glass panes. When the proper degree of snugness is attained the bolts 28 are tightened to lock the structure together. These clamping bolts are spaced at intervals along the unit as will be readily understood. A feature of these division and corner unit constructions is that they are exceptionally well adapted for adjustment to accord with varying conditions in different installations. The fact that one glass pane may be thicker than another is conformed with by the independent action of the glass engaging bars 26. As in the previously described sash construction, the set plates 27 cooperate with the softer tie bar 24 to securely lock the elements of the unit in a given position of adjustment.

Figures 2 and 3 also show the addition of a reinforcing member 31 comprising two sections clamped about the inwardly projecting portion of the unit by suitable bolts 32. This reinforcing member adds to the rigidity of the construction, and may be found desirable under certain conditions. Of course this reinforcement may also be employed in the corner unit illustrated in Figure 4. The corner unit however is an inherently stronger construction, and the reinforcing consequently does not find as many applications at this point of the construction.

Figures 10 and 11 illustrate a variant form of sash construction embodying the improvements of my invention. This structure is similar to that shown in Figure 1, except that in the present instance the tie bar 33 is pivotally and slideably mounted on the glazing bar. This arrangement gives an additional amount of adjustability. The mounting of the tie bar 33 is provided by forming a cylindrically shaped socket in the glazing bar adapted to receive a similarly shaped end 34 on the tie bar. The transverse adjustment provided by the pivotal mounting of the tie bar eliminates any possibility of undue strain on the glass when the structure is being assembled and locked. The longitudinal adjustment of the tie bars along the sash gives a flexibility to the construction which is useful in the setting of the setting blocks and in the assembly of the unit after the pane and its blocks have been set.

Figures 10 and 11 also illustrate a variant form of construction, in which the tie bar 33 is made of harder material than the set plate 36; the teeth then of course being provided on the under side of the bar, as is clearly shown in Figure 11. In this construction the plate 36 may conveniently be of the softer metals, such as Babbitt or type metal. Of course it is understood that this reversal in the mounting of the teeth is applicable to the constructions shown in Figures 1, 2 and 4. That is, the teeth in the latter structures could be formed on the tie bars, and set plates made of the softer material.

The modified structure of Figures 10 and 11 has the advantage of an independently formed tie bar. This gives a wider selection of materials in the making of the tie bar. In the integral construction of Figure 1 the materials employed in the tie bar are limited to those suitable for the glazing bar. This limitation however is not imposed in the modified construction.

It is understood that formation of the teeth on the tie bar or set-plate is subject to variation within wide limits. Protuberances such as

shown in Figures 6 and 7 may be provided, or teeth may be formed by knurling or scoring the surface of the metal. It is further understood that an independent set-plate need not be provided. For example, the toothed tie bar may be imbedded directly into the sash bar. This is particularly true of the construction shown in Figures 10 and 11, where the demountable toothed tie bar may be made of a material selected primarily for its hardness.

I claim:

1. A glass holding construction comprising a pair of glass engaging bars, a toothed element on one of the bars, a deformable element on the other bar, and pressure means mounted on the bar carrying the deformable elements and bearing against the toothed element for embedding the teeth of the latter into the deformable element for locking said bars together.
2. A glass holding construction comprising a glass engaging bar having a longitudinally extending groove, a second glass engaging bar, a toothed plate slidably mounted in said groove, a deformable element on the other bar, and means for embedding the teeth of the first element into the second element for locking said bars together.
3. A glass holding construction comprising a glass engaging bar having a longitudinally extending dove-tailed groove, a second glass engaging bar, a toothed plate slidably mounted in said groove, a deformable element on the other bar, and means for embedding the teeth of the first element into the second element for locking said bars together.
4. A sash for holding glass comprising a grooved stationary sash bar, a movable sash bar, a tie bar mounted on said movable sash bar, a plate slidably mounted in the groove of the stationary sash bar, said tie bar and plate comprising materials of different hardness and the harder of the two latter elements having teeth adapted to be embedded in the softer material of the other, and means for clamping the tie bar and plate together for holding the sash bars against separation.
5. A sash for holding glass comprising a channel-shaped stationary sash bar, a movable sash bar, a tie bar mounted on the movable sash bar and projecting between the flanges of the stationary sash bar, a plate seated on one of the flanges of said latter bar, said tie bar and plate comprising materials of different hardness and the harder of the two latter elements having teeth adapted to be embedded in the softer material of the other, and a screw threaded in the other flange of the stationary sash bar and bearing against the tie bar for holding the sash bars against separation.
6. A glass holding construction comprising a sash bar having a longitudinally extending groove, a plate slidably mounted in said groove, a second sash bar, a tie bar on the latter bar and overlying

said plate, said tie bar and plate comprising materials of different hardness and the harder of the two having teeth adapted to be imbedded in the softer material of the other, and means for clamping the tie bar and plate together to hold the sash bars against separation. 5

7. A glass holding construction comprising a sash bar having a flange provided with a longitudinally extending groove, a plate slidably mounted in said groove with its upper surface lying substantially in the surface plane of said flange, a second sash bar, a tie bar on the latter bar and overlying said plate, said tie bar and plate comprising materials of different hardness and the harder of the two having teeth adapted to be imbedded in the softer material of the other, and means for clamping the tie bar and plate together to hold the sash bars against separation. 10 15

8. A glass holding construction comprising a sash bar having a flange provided with a longitudinally extending groove, a plate slidably mounted in said groove with its upper surface lying substantially in the surface plane of said flange, a second sash bar, a tie bar formed integrally with said latter bar and overlying said plate, 20 25 said tie bar and plate comprising materials of different hardness and the harder of the two having teeth adapted to be imbedded in the softer material of the other, and means for clamping the tie bar and plate together to hold the sash bars 30 against separation.

9. A glass holding construction comprising a channel-shaped stationary sash bar, a movable sash bar, a tie bar on the movable sash bar projecting into the channel bar and adjacently overlying one of its flanges, said flange having a longitudinally extending groove lying within the channel, a plate slidably in the groove and positioned under the tie bar, said tie bar and plate comprising materials of different hardness and the harder of the two having teeth adapted to be imbedded in the softer material of the other, and means for clamping the tie bar and plate together to hold the sash bars against separation. 35 40

10. A glass holding construction comprising a channel-shaped stationary sash bar, a movable sash bar, a tie bar on the movable sash bar projecting into the channel bar and adjacently overlying one of its flanges, a lip on the movable sash bar and spaced from the tie bar to engage under said channel flange, said flange having a longitudinally extending groove lying within the channel, a plate slidably in the groove and positioned under the tie bar, said tie bar and plate comprising materials of different hardness and the harder of the two having teeth adapted to be imbedded in the softer material of the other, and means for clamping the tie bar and plate together to hold the sash bars against separation. 45 50 55
